UNITED STATES PATENT OFFICE.

MARY OSBON, OF BALTIMORE, MARYLAND.

HAT OR DRESS FASTENER.

SPECIFICATION forming part of Letters Patent No. 699,559, dated May 6, 1902.

Application filed September 13, 1900. Renewed October 31, 1901. Serial No. 80,673. (No model.)

To all whom it may concern:

Be it known that I, MARY OSBON, a citizen of the United States, residing at Baltimore, in the State of Maryland, have invented certain 5 new and useful Improvements in Ladies' Hat or Dress Fasteners, of which the following is a specification.

My invention relates to hat and dress fasteners; and one of its objects is to provide a 10 device of this character which will have the appearance of a row of buttons when applied to the front of a dress-body to hold the same closed, which will render a dress-body easy to fasten and unfasten, and which will readily 15 conform to the figure of the wearer.

Another object of the invention is the construction of the fastener device which makes it applicable to hats and which when applied to a hat will prevent the latter from shifting 20 or skewing around on the wearer's head.

Reference is to be had to the accompanying drawings, in which—

Figure 1 is a side view of a dress-body provided with my improved fastener. Fig. 2 is 25 an enlarged front view of a portion of the meeting vertical edges of a garment fastened together with my device. Fig. 3 is a front view of a portion of the fastener. Fig. 4 is a longitudinal sectional view on the line 4 4 of Fig. 3. 30 Fig. 5 is a transverse sectional view on the line 5 5 of Fig. 2. Fig. 6 is a transverse vertical sectional view of a hat with the fastener applied thereto. Fig. 7 is a detail view of a modified form of hook used in connection with 35 the fastener.

Referring to the drawings, *a* designates a strip of flexible material stamped with a row of bead-like heads or button-heads *b*, which are hollow and of convex shape, standing out 40 from the flat body portion *c* of the flexible strip and are contiguous to each other, thereby simulating a row of buttons placed closely together. The flat body portion *c* of the said flexible strip extends along each side of the 45 row of button-heads and is provided along its edges and between the button-heads *b* with two series of apertures *d d'*, each of which series is availed of for the engagement of any suitable attaching means to secure the 50 said strip *a* to the vertical meeting orlapping edges of a garment. For instance, the

series of apertures *d* along one edge of the strip *a* may be availed of for detachably or permanently attaching one edge of the said strip to a vertical edge of a garment, while 55 the series of apertures *d'* along the other edge of said strip receives at desired intervals one of the prongs of a two-pronged hook *e*. The other prongs of said hooks take in the other vertical edge of the garment, and thereby hold 60 the said two edges together. As shown at *f*, Fig. 2, ornaments are preferably attached to the said hooks to conceal the same and to add to the appearance of the fastener.

The flexibility of the strip *a* allows it to 65 readily conform to a wearer's figure, as indicated in Fig. 1, and the button-heads in no wise interfere with the curving of the strip and cause it to possess the same general appearance when it is curved that it possesses 70 when straight.

Fig. 6 illustrates the fastener applied to a hat *g*. The flexible strip *a* is sewed or otherwise secured by one edge around the inside of the hat-crown at the lower edge thereof. 75 With this arrangement of the flexible strip *a* I may employ two hooks *h*, located at diametrically opposite points of the hat, each hook having two prongs *i* extending toward each other and joined together by a spring-coil portion *j*. One of the prongs *i* takes in 80 one of the apertures *d'* along that edge of the flexible strip *a* which is unattached to the hat-crown, and the other prong engages the wearer's hair. 85

What I claim as new, and desire to secure by Letters Patent, is—

1. As a new article of manufacture, a hat and dress fastener comprising a flexible strip provided with a row of hollow, convex button-heads, contiguous to each other, whereby to simulate a row of buttons placed closely together, and also having a body portion provided along each edge with a series of apertures each series adapted to receive suitable attaching means, as and for the purpose set forth.

2. A dress-fastener, comprising a flexible strip provided with a row of hollow, convex button-heads contiguous to each other, and also provided along each edge with a series of apertures; means engaging the apertures

along one edge of said strip whereby to secure said edge to one edge of a garment; and two pronged hooks secured by one prong at intervals in the apertures along the other edge of said strip, with the other prongs of said hooks taking in the opposing edge of the garment, as and for the purpose set forth.

In testimony whereof I have signed my name to this specification in the presence of two subscribing witnesses.

MARY OSBON.
